UNITED STATES PATENT OFFICE.

CHARLES P. COTTRELL, OF WESTERLY, RHODE ISLAND, ASSIGNOR, BY MESNE ASSIGNMENTS, TO C. B. COTTRELL & SONS COMPANY, OF NEW YORK, N. Y., A CORPORATION OF DELAWARE.

OFFSET MECHANISM FOR PRINTING-PRESSES.

1,148,010.

Specification of Letters Patent. Patented July 27, 1915.

Application filed August 23, 1911. Serial No. 845,499.

To all whom it may concern:

Be it known that I, CHARLES P. COTTRELL, a citizen of the United States, and resident of Westerly, in the county of Washington 5 and State of Rhode Island, have invented a new and useful Improvement in Offset Mechanism for Printing-Presses, of which the following is a specification.

This invention relates to improvements in 10 offset mechanism for printing presses and has for one of its objects to provide novel means for introducing a printed product into an offset web winding roll in which the roll is fed at a constantly diminishing rotary speed so that its web may be fed at 15 a uniform linear speed.

Another object is to provide means for introducing printed sheets cut and fed from a web, or sheets fed from a source of cut 20 sheet supply, into the offset web winding roll.

A still further object is to provide means for utilizing the offset web as a carrier for feeding the sheets into the offset web winding roll.

A still further object is to provide means for manually controlling the operation of the driving mechanism for the offset web winding roll.

In the accompanying drawings, Figure 1 is a view in side elevation of so much of the sheet delivery mechanism of a printing press as will give a clear understanding of my invention, Fig. 2 is a horizontal section 35 through the same taken in the planes of the line A—A of Fig. 1, and with the offset web roll removed, Fig. 3 is a detail front view of the variable speed driving mechanism with the parts in a different position from that shown in Figs. 1 and 2, Fig. 4 is a detail side view of the same, Fig. 5 is a detail section showing more clearly the means for adjusting the throw of the crank on the driving shaft, and Fig. 6 is a detail side view 45 of the variable speed mechanism with the parts in a third position.

The offset web is denoted by 1, its supply roll and shaft by 2 and 3; and its winding roll and shaft by 4 and 5. The supply roll 3 is removably mounted in bearings 6

and is provided with a suitable friction brake mechanism 7 of well known or approved form for regulating the tension on the web supply roll 2. The offset web 1 passes from the supply roll 2 first around 55 a guide roll 8 and from thence over a guide roll 9. The printed sheets may be fed onto the web 1 from guides 10 in any suitable manner.

I will now proceed to describe the variable 60 speed driving mechanism which is arranged to drive the offset web at a uniform linear speed of travel, which mechanism is so proportioned that when on its highest speed it will drive the empty core on the winding 65 shaft 5 fast enough to take care of the sheets from the press and will gradually diminish the rotary speed of the winding roll shaft as the roll increases in size so as to keep the offset web traveling at a uniform linear 70 speed. The horizontally arranged driving shaft 11 is mounted in suitable bearings 12, 13, which shaft is driven from the press at a predetermined speed through the horizontal shaft 14, double gear connections 15, 75 16, vertical shaft 17 and bevel gear connections 18, 19. One bearing 20 for the shaft 14 is shown and a bearing 21 for the vertical shaft 17 is shown as carried by a bracket 22 secured to the side framing 23 of the machine. This drive shaft 11 is provided with 80 a pair of cone pulleys 23, 24, arranged to be moved toward and away from each other by suitable mechanism to be hereinafter described.

A horizontally arranged driven shaft 25 is mounted in suitable bearings 26, 27, which shaft is provided with a pair of cone pulleys 28, 29, arranged to be moved toward and away from each other in the opposite direction to the movement of the pulleys 23, 24, on the driving shaft 11. A belt 30 passes around these two pairs of cone pulleys. This shaft 25 is provided with a pulley 31 and the winding roll shaft 5 is provided 95 with a pulley 32 around which a driving belt 33 passes. This driven shaft 25 is further provided with a slotted crank disk 34.

An intermittently rotated shaft 35 is provided with a suitable bearing 36, which shaft 100

is provided with right and left hand screw threaded portions 38, 39, engaging nuts 40, 41, at the corresponding ends of horizontally rocking levers 42, 43, pivoted at 44, 45, to 5 brackets 46, 47. The rotation of this shaft 35 gradually moves one pair of cone pulleys toward each other and the other pair of cone pulleys away from each other by providing the levers 42, 43, with yoke connections 48, 10 49, with the cone pulleys 23, 24, and with yoke connections 50, 51, with the cone pulleys 28, 29. The intermittent rotary movement of this shaft 35 for gradually decreasing the rotative speed of the shaft 25 and thereby the winding roll shaft 5, is accomplished by a pawl and ratchet connection between the shaft 35 and the crank 34 on the driven shaft 25 as follows:—A ratchet wheel 52 is fixed to the shaft 35 and a friction device, such, for instance, as a spring 53, is interposed between the ratchet wheel and the bearing 36 for preventing a reverse movement of the ratchet wheel.

25 A pair of pawls 54, 55, are mounted on a rocking arm 56 loosely mounted on the end of the shaft 35 and a pitman rod 57 connects this arm 56 with the crank 34.

30 Manually operated means are provided for adjusting the throw of the crank 34, and thereby the rotative movement of the shaft 35, without stopping the operation of the parts, as follows:—The pitman rod 57 is connected to a nut 58 fitted to be moved radially in a groove 59 in the crank 34 by 35 a screw 60. The head of this screw is provided with a plurality of arms 61, and two manually operated levers 62, 63, are provided, the lever 62 being rocked into position to engage one of the arms 61 on the screw 60 when it is desired to turn the screw for lengthening the stroke and the lever 63 is rocked in position to engage one of the arms 61 on the screw when it is desired to turn the screw in a direction to shorten the 45 stroke. In Fig. 6 the lever 62 is shown rocked into position to engage the screw for lengthening the stroke.

50 The driving connection between the driven shaft 25 and the screw shaft 35 may be rendered inoperative at any time without stopping the mechanism, as follows:—A segment 64 is carried by one arm 65 of a rock lever and the other arm 66 of which lever is connected to a hand lever 67 by a 55 rod 68. This segment 64 projects over the ratchet wheel 52 and may be rocked into a position between the pawls 54, 55, and the ratchet wheel 52 for rendering the pawls inoperative whenever desired.

60 From the above description it will be seen that the speed of rotation of the offset web winding roll shaft is completely under the control of the operator at all times with-

out the necessity of stopping the driving mechanism, thus permitting the operator to 65 cause the offset web to be moved at a pre-determined linear speed or just fast enough to take care of the printed product as it is fed thereto.

It is to be understood that I do not wish 70 to limit myself to any means for feeding the printed product into the offset web winding roll, the invention being directed to the means for moving the web at a predetermined linear speed by means of a variable 75 speed driving mechanism having manually operated devices for controlling the said variable speed driving mechanism.

What I claim is:—

1. An offset web winding roll, its shaft, 80 a variable speed driving mechanism for driving the winding roll shaft at a gradually diminishing rotative speed to cause the web to travel at a uniform linear speed and means for feeding printed sheets into the roll.

2. An offset web winding roll, its shaft, a variable speed driving mechanism for driving the winding roll shaft at a gradually diminishing rotative speed to cause the web 90 to travel at a uniform linear speed, manually operated means acting on the variable speed driving mechanism for causing it to drive the winding roll shaft at an increased or decreased rotative speed when so desired, 95 and means for feeding printed sheets into the roll.

3. An offset web winding roll, its shaft, a variable speed driving mechanism for driving the winding roll shaft at a gradually 100 diminishing rotative speed to cause the web to travel at a uniform linear speed, manually operated means acting on the variable speed driving mechanism for causing the winding roll shaft to be driven at a uniform 105 rotative speed when so desired, and means for feeding printed sheets into the roll.

4. An offset web roll, means for driving the roll at a gradually diminishing rotative speed, manually operated means for causing 110 the roll to be driven at an increased, decreased or uniform rotative speed when so desired, and means for feeding printed sheets into the roll.

5. An offset web supply roll, an offset web 115 winding roll, its shaft, a variable speed driving mechanism for driving the winding roll shaft at a gradually diminishing rotative speed to cause the web to travel at a uniform linear speed, and means for feeding printed sheets on to the offset web between the supply roll and winding roll.

6. An offset web supply roll, an offset web winding roll, its shaft, intermediate guide rolls over which the web passes from the 120 supply roll to the winding roll, a variable 125

speed driving mechanism for driving the winding roll shaft at a gradually diminishing rotative speed to cause the web to travel at a uniform linear speed, and means for feeding printed sheets on to the web between said guide rolls.

5 In testimony, that I claim the foregoing

as my invention, I have signed my name in presence of two witnesses, this twenty first day of August A. D. 1911.

CHARLES P. COTTRELL.
